[57] CLAIM

The ornamental design for a self-service facility, as shown and described.

DESCRIPTION

FIG. 1 is a front view of a self-service facility with the revolving door open, showing our new design;

FIG. 2 is a front view of the self-service facility with the revolving door closed;

FIG. 3 is a back view of the self-service facility;

FIG. 4 is a top view of the self-service facility;

FIG. 5 is a bottom view of the self-service facility;

FIG. 6 is a side view of the self-service facility;

FIG. 7 is a cross-sectional view of the self-service facility along the axis shown in 7—7 in FIG. 1;

FIG. 8 is a perspective view of the self-service facility with the revolving door closed;

FIG. 9 is a perspective view of the self-service facility with the revolving door partially open; and,

FIG. 10 is a perspective view of the self-service facility with the revolving door open.

The inventors' design is directed toward a self-service facility with a revolving semicircular door. The self-service facility may be free-standing, or it may be attached to a wall of a structure.

The broken lines are for illustrative purposes only and form no part of the claimed design.
